UNITED STATES PATENT OFFICE

2,451,455

CRANK ARM AND DRIVING BLOCK MEANS

David S. Willson, Muskegon Heights, Mich., assignor to John Wood Manufacturing Company, Inc., Philadelphia, Pa., a corporation of Delaware

Application June 23, 1945, Serial No. 601,180

13 Claims. (Cl. 74—60)

1

My invention relates to improvements in crank arm and driving block means for positive displacement meters of the nutating type. My improved crank arm and driving block means are also adaptable for other uses, such as for installation in other types of structures which include a nutating disc or plate, etc.

One feature of my invention is that my improved crank arm and driving block construction facilitates the assembling of meters.

Another feature of my invention is that the spring loading which holds the wobble plate down on its spherical seat is separated from the spring loading exerted sidewise on the wobble plate spindle. Accordingly, the wobble plate is held effectively on its track during normal operation. In my improved construction, each force is in a direct and controllable relationship and, hence, adjustment for calibration is facilitated.

Another feature of my invention is that my improved crank arm and driving block assembly will permit the wobble plate to rise from its track in the event some hard foreign object of comparatively small size be present on the track. Although my improved construction permits the wobble plate to leave the track under such a condition, the movement of the wobble plate from the track is limited to predetermined value to insure proper performance.

Another feature of my invention is that its use permits the free operation of a meter when the crankshaft and the spherical bearing for the wobble plate are slightly out of axial alignment. Such condition is bound to occur occasionally in the making of production runs of the component parts of meters.

Conveniently, I have shown my improved crank arm and driving block assembly embodied in a fluid meter of the general type which is described and claimed in my co-pending applications Serial No. 569,477, filed December 23, 1944, now Patent No. 2,413,670, dated December 31, 1946, and Serial No. 569,478, filed December 23, 1944.

In said drawings; Fig. 1 is a vertical sectional view, partly in elevation, of a fluid meter embodying my invention.

Fig. 2 is a plan view of the crank arm and driving block assembly means shown in Fig. 1.

Fig. 3 is a vertical sectional view, partly in elevation, of the structure shown in Fig. 2, taken on the lines 3—3 in Fig. 2.

Fig. 4 is an elevation of the crank arm and driving block assembly attached to the crankshaft, as indicated in Fig. 1.

Referring to said drawings; I have shown my

2

invention embodied in a meter which conveniently is formed in three parts comprising the top cover 1, main body casing 2, and base portion, or bottom closure, 3. Said top cover 1 is rigidly connected to the body casing 2 by means of a circumferential series of bolts which extend through openings in the top cover 1 into matching screw threaded holes in the top of the body casing 2. I find it convenient to interpose a gasket 5 between the top cover 1 and the body casing 2 in order to maintain said top cover 1 and body casing 2 in fluid tight relationship. Said bottom closure 3 is rigidly connected to the body casing 2 by a circumferential series of bolts 6, one of which is indicated in Fig. 1, which extend through openings in the flange of the bottom closure 3 into matching screw threaded holes formed in the bottom of the body casing 2. I find it convenient to interpose the gasket 7 between the bottom closure 3 and the body casing 2 to maintain said bottom closure 3 and body casing 2 in fluid tight relationship.

Said bottom closure 3 is provided with the inlet opening 9 which is in registry with the inlet passageway 10 formed in the body casing 2. Said inlet passageway 10 is in open communication with the inlet chamber 11 formed in the top cover 1. Said meter is adapted to be mounted with the inlet opening 9 in registry with, or connected to, a source of fluid under pressure which is measured as it passes through the meter. For example, in Fig. 1 I have shown the meter mounted on the top of an air eliminator chamber, indicated in dotted lines, of a gasoline dispensing apparatus and with the inlet opening 9 in registry with the outlet opening 12 formed in the top cover 13 of said air eliminator.

The valve seat 15 is formed conveniently as a separate flat plate which is rigidly connected to the top wall 16 of the body casing 2 by means of a series of screws extending through openings in said valve plate 15 into engagement with matching screw threaded holes in said top wall 16. Said valve plate 15 is provided with a series of port openings 17 therethrough which are in registry with openings 18 formed in the top wall 16 of the body casing 2. Each port 17 is in open communication with its piston cylinder 20. I find it convenient to form said piston cylinders 20 as pressed, or stamped, inverted steel cups which are rigidly connected to the underside of the top wall 16 by screws 21 which extend through openings in the top walls 22 of the cups 20 into screw threaded holes formed in the top wall 16. The top wall 22 of each cylinder cup 20 is provided

with an opening 23 which is in registry with the port opening 17 for that piston cylinder. The meter shown in Fig. 1 is of the three-piston cylinder type, although only the piston and cylinder coming in the line of section is shown for purposes of clarity.

Each of the cylinders 20 is provided with a piston assembly which is mounted in a cylinder 20 for reciprocation in response to fluid pressure on the top of the piston. Each piston assembly includes a cup leather 25, piston backing plate 26, intermediate plate 27, piston spring retainer plate 28 and piston expander spring 30, all of which are assembled together by means of a series of screws 31, one of which is shown in Fig. 1. The piston assembly shown and described is of the well known construction wherein the piston expander spring 30 is adapted to maintain the upturned edge of the cup leather 25 in continuous frictional engagement with the side wall of the cylinder 20.

The piston includes a telescopic connecting rod consisting of the outer tubular member 32 which is adaptable for sliding engagement on the inner member 34. The piston assembly is mounted on the screw threaded reduced portion 35 of the outer tubular connecting rod member 32, and maintained in rigid position on the member 32 by means of a nut 36. The telescopic connecting rod shown herein is described and claimed in my copending application Serial No. 584,720 filed March 24, 1945. The inner member 34 of the telescopic connecting rod is provided at its lowermost end with a ball end 37 which is mounted and confined in the socket 38 formed in the wobble plate 40. The ball end 37 is retained conveniently in its socket 38 by means of a washer 41 and snap ring 42.

The wobble plate 40 is provided with the socket 45 and said wobble plate 40 is concentrically mounted in the chamber 46 of the body casing 2 on the hemispherically shaped ball end 47 of the adjusting screw 48. Rotation of the wobble plate 40 is prevented by the pin 50, rigidly mounted in a boss formed in the bottom closure 3, which extends through an elliptically shaped opening formed in the web of the wobble plate 40. The use of an elliptically shaped opening and pin extending therethrough to permit nutation of a wobble plate, but to prevent rotation thereof, is well known in the art.

The adjusting screw 48 is in screw threaded relationship with the screw threaded opening 52 of the boss 53 formed in said bottom closure 3. Said adjusting screw 48 has a reduced stem portion 54, on the lower end of which is rigidly connected to worm gear 56. The reduced stem portion 54 is provided with packing and a packing ring retained in position by the spring 57, the upper end of which engages the packing ring and the lower end of which engages the bottom of the socket 59 formed in the hub of said worm gear 56. Said worm gear 56 is in engagement with the worm 60 which is rigidly mounted on the worm shaft 61. Said worm shaft 61 is provided at its outer end not shown, with a screw driver slot for conveniently effecting movement of said worm and worm gear. Calibrating adjustment of the meter may be effected by inserting a screw driver in the slot in the end of the worm shaft 61 to turn the worm 60 to effect clockwise or counterclockwise movement of the worm gear 56, to raise or lower the roundheaded adjusting screw 48 and wobble plate 40 in engagement therewith, to thus shorten or lengthen

the stroke of the pistons in their respective cylinders 23.

As shown in Figs. 1, 2 and 3, the wobble plate 40 is provided with the driving stem shaft 62 which is journaled in the drilled opening 63 formed in the driving block 65. Said driving block 65 is slidably mounted with freedom of pivotal movement on the crank arm pin 67, which extends through the elongated opening 75 formed in the driving block 65. The outer ends of said pin 67 extend respectively through the bifurcated crank arms 68 formed on the crank 70. Said crank arm pin 67 is provided at one end with the enlarged head 72, and the opposite end of said pin 67 is provided with the cotter pin 73, extending through the drilled opening 74, for retaining said pin 67 in position. The driving block 65 is provided with the spring 76 held between the inner cup washer 78, which engages the ends of the bifurcated crank arms 68, and the outer washer 80 which is mounted on the reduced portion 81 formed at the right-hand end of the driving block 65, as viewed in Fig. 3. As shown in Figs. 2 and 3, the inner cup washer 78 is maintained in sliding engagement with the outer ends of the bifurcated crank arms 68.

The outer washer 80 is maintained in position at the end of the driving block 65 by means of the screw 83 which is engaged in the screw threaded socket 84 formed at the right-hand end of the driving block 65.

Such driving block assembly places a loading on the wobble plate stem shaft 62 substantially at right angles to the axis of said shaft 62, with the result that all of the forces of the spring 76 act to hold the wobble plate 40 on the wobble plate track 85 formed on the upper side of the bottom closure 3, as shown in Fig. 1.

Said wobble plate 40 is provided with the spring 86, the lower end of which encircles and engages the offset 87 formed at the top of the wobble plate 40. The upper end of said spring 86 is in engagement with the wobble plate bearing washer 89. The thrust washer 90 is interposed between the wobble plate bearing washer 89 and the bottom surface of the bifurcated arms 68. Said thrust washer 90 is provided with the upturned portion 91 which is engaged with freedom of movement between the bifurcated arms 68, as best shown in Fig. 3.

The crank arm 70 is rigidly connected to the reduced screw threaded lower end portion of the crankshaft 93 by means of the castle nut 94. The lower end of the crankshaft 93 is provided with the reduced flattened portion 95 which engages the slot 96 formed in the top of the crank arm 70. Such construction effects a keying between the crankshaft 93 and the crank arm 70. Said crankshaft 93 is journaled in the thrust bearings 97 and 98 which are press fitted in the opening 100 formed in the bearing 101 which is formed conveniently as an integral part of the main body casing 2.

The crankshaft 93 is provided at its upper end, in integral relation therewith, with the crank arm 102 and crank pin 103 which drive the meter valve 105. The crankshaft 93 rotates in a clockwise direction, and it is to be noted that the crank arm 70, at the lower end of the crankshaft 93, is fastened to said crankshaft 93 at substantially 90 degrees clockwise from the crank arm 102 which drives the meter valve 105. The valve 105 is operatively connected to the drive shaft arm 106 which is rigidly fastened to the lower end of the drive shaft 107. Said drive shaft 107 is adapted

to be connected at its upper end, by any convenient means, to a recording mechanism which registers the volume of fluid passed by the meter.

The valve plate 15 is provided with a series of outlet ports 110, one of which is shown in Fig. 1, which are in registry with outlet openings 112 formed in the top wall 16 of the body casing 2. Said outlet openings 110 are in open communication with the meter chamber 46, which is in open communication with the meter outlet passageway (not shown) formed in the meter bottom closure 3.

Assuming the meter to be completely filled with liquid as installed in a conventional type of gasoline pump, such as is described in Letters Patent of the United States No. 2,351,331 granted June 13, 1944, to M. J. Goldberg, the meter inlet opening 9 is connected to the outlet opening 12 in the top cover 13 of the air eliminator. With liquid being dispensed through the meter, the liquid under pressure flows up the inlet passageway 18 to the inlet chamber 11 formed in the top cover 1. The liquid under pressure from the inlet chamber 11 enters through a port 17 to the cylinder 20 for that port, which forces the piston assembly in that cylinder downwardly. Such downward movement moves the wobble plate 40, thus causing the crankshaft 93 to revolve clockwise. Clockwise movement of the crankshaft 93 moves the valve 105 clockwise which, depending on the position of the valve, opens or closes the ports 17 leading to the cylinders 20. As the meter operates, liquid is forced downwardly through the outlet port openings 110 to the chamber 46 and thence through the meter outlet formed in the bottom of the meter. In liquid dispensing apparatus, the outlet from the meter is connected to the valve control dispensing nozzle of such apparatus.

Calibration of the meter is effected by turning the shaft 61 clockwise or counter-clockwise to effect increase or decrease in the quantity of fluid discharged by the meter per cycle of operation, as turning movement of the adjusting shaft 61 causes the worm 60 to turn the gear 56. The gear 56 being rigidly fastened to the adjusting screw 48, movement of the gear 56 causes the adjusting screw to be raised or lowered in the screw threaded opening 52 formed in the boss 53 of the bottom closure. The hemispherically shaped ball end 41 of the adjusting screw 48 being engaged in the socket 45 of the wobble plate 40, raising and lowering of the adjusting screw 48 causes the center portion of the wobble plate 40 to be raised or lowered to change the length of the stroke of the pistons in the cylinders 20.

As the driving block 65 is slidably mounted with freedom of pivotal movement on the crank arm pin 67 extending through the elongated opening 75 formed in the driving block 65, when the center portion of the wobble plate 40 is raised or lowered the driving block 65 moves about the crank arm pin 67 as a pivot and also moves endwise within the limits defined by the pin 67 coming into engagement with either end of the elongated opening 75 formed in the driving block 65. Therefore, regardless of the position of the driving block 65 with respect to the bifurcated arms 68 of the crank arm 70, the forces of the spring 76 always place a loading on the wobble plate stem shaft 62 substantially at right angles to said shaft 62. Hence, all the forces of the spring 76 act to hold the wobble plate 40 on the wobble plate track 85 formed on the upper side of the bottom closure 3. The forces of the spring 86

which holds the wobble plate 40 down on the spherical seat 47 are always exerted in a direction substantially coinciding with the axis of the wobble plate 40, and such axial spring loading of the wobble plate is separate from the spring loading exerted sidewise on the wobble plate spindle.

It is obvious that various modifications may be made in my invention without departing from the essential features thereof as defined in the appended claims, and, therefore, I do not desire to limit myself to the precise details of construction and arrangement herein set forth.

I claim:

- 15 1. A crank arm and driving block assembly comprising a driving block in which a drive shaft is adapted to be journaled; a crankshaft; a crank arm operatively connected to said crankshaft; means connecting said driving block to said crank arm with freedom of sliding movement about a fixed pivot; and spring loading means for said driving block wherein the forces of said spring loading means are exerted on said drive shaft substantially at right angles to the axis of said drive shaft.
- 20 2. In a fluid meter; the combination with a wobble plate; of a drive shaft on said wobble plate; a driving block in which said drive shaft is journaled; a crankshaft; a crank arm operatively connected to said crankshaft; means connecting said driving block to said crank arm with freedom of sliding movement about a fixed pivot; and spring loading means for said driving block wherein the forces of said spring loading means are exerted on said wobble plate drive shaft substantially at right angles to the axis of said wobble plate drive shaft.
- 25 3. In a fluid meter; the combination with a wobble plate; of a drive shaft on said wobble plate; a driving block in which said drive shaft is journaled; a crankshaft; a crank arm operatively connected to said crankshaft; bifurcated arms formed on said crank arm; means connecting said driving block to said bifurcated arms with freedom of sliding pivotal movement; and spring loading means for said driving block wherein the forces of said spring loading means are exerted on said wobble plate drive shaft substantially at right angles to the axis of said wobble plate drive shaft.
- 30 4. In a fluid meter; the combination with a wobble plate; of a drive shaft on said wobble plate; a driving block in which said drive shaft is journaled; a crankshaft; a crank arm operatively connected to said crankshaft; bifurcated arms formed on said crank arm; means extending through said elongated opening and connecting said driving block to said crank arm within said bifurcated arms with freedom of sliding pivotal movement; and spring loading means for said driving block wherein the forces of said spring loading means are exerted on said wobble plate drive shaft substantially at right angles to the axis of said wobble plate drive shaft.
- 35 5. In a fluid meter; the combination with a wobble plate; of a drive shaft on said wobble plate; a driving block in which said drive shaft is journaled; an elongated opening in said driving block; a crankshaft; a crank arm operatively connected to said crankshaft; bifurcated arms formed on said crank arm; a crank arm pin extending through said elongated opening and bifurcated arms and connecting said driving block within said bifurcated arms with freedom of slid-

ing pivotal movement; and spring loading means for said driving block wherein the forces of said spring loading means are exerted on said wobble plate drive shaft substantially at right angles to the axis of said wobble plate drive shaft.

6. In a fluid meter; the combination with a wobble plate; of a drive shaft on said wobble plate; a driving block in which said drive shaft is journalled; an elongated opening in said driving block; a crankshaft; a crank arm operatively connected to said crankshaft; arms formed on said crank arm; a crank arm pin extending through said elongated opening and arms and connecting said driving block within said arms with freedom of sliding pivotal movement; and a spring operatively connected to said driving block wherein the forces of said spring are exerted on said wobble plate drive shaft substantially at right angles to the axis of said wobble plate drive shaft.

7. In a fluid meter; the combination with a wobble plate; of a drive shaft on said wobble plate; a driving block in which said drive shaft is journalled; an elongated opening in said driving block; a crankshaft; a crank arm operatively connected to said crankshaft; a pair of spaced arms formed on said crank arm; a crank arm pin extending through said elongated opening and said pair of spaced arms and connecting said driving block between said arms with freedom of sliding pivotal movement; a spring operatively connected to said driving block; and means at the opposite ends of said spring for confining said spring; whereby, the forces of said spring are exerted on said wobble plate drive shaft substantially at right angles to the axis of said wobble plate drive shaft.

8. In a fluid meter; the combination with a wobble plate; of a drive shaft on said wobble plate; a driving block in which said drive shaft is journalled; an elongated opening in said driving block; a crankshaft; a crank arm operatively connected to said crankshaft; a pair of spaced arms formed on said crank arm; a crank arm pin extending through said elongated opening and said pair of spaced arms and connecting said driving block between said arms with freedom of sliding pivotal movement; a spring operatively connected to said driving block; an inner cup washer and an outer retaining washer embracing the respective opposite ends of said spring for confining said spring under compression; and screw means extending through said cup washers and spring into said driving block; whereby, the forces of said spring are exerted on said wobble plate drive shaft substantially at right angles to the axis of said wobble plate drive shaft.

9. A structure as in claim 8; wherein the inner cup washer is in sliding engagement with the outer ends of said pair of arms formed on said crank arm.

10. In a fluid meter; the combination with a wobble plate; of a drive shaft on said wobble

plate; support means for said wobble plate; a track for said wobble plate; a driving block in which said drive shaft is journalled; an elongated opening in said driving block; a crankshaft; a crank arm operatively connected to said crankshaft; a pair of spaced arms formed on said crank arm; a crank arm pin extending through said elongated opening and said pair of spaced arms and connecting said driving block between said arms with freedom of sliding pivotal movement; a spring operatively connected to said driving block; an outer retaining washer at the outer end of said spring; an inner cup washer embracing the inner end of said spring, said inner cup washer being in abutting engagement with the outer ends of said pair of arms; retaining means extending through said cup washers and spring into said driving block; and a second spring for holding said wobble plate in engagement with said wobble plate support means.

11. A structure as in claim 10; wherein, said second spring encircles said wobble plate drive shaft and wherein said second spring is positioned between the underside of said pair of spaced arms and the top of said wobble plate.

12. A crank arm and driving block assembly comprising a driving block in which a drive shaft is adapted to be journalled; a crankshaft; a crank arm operatively connected to said crankshaft; means connecting said driving block to said crank arm with freedom of sliding pivotal movement of the block about said means connecting said driving block to said crank arm; and spring loading means for said driving block wherein the forces of said spring loading means are exerted on said drive shaft substantially at right angles to the axis of said drive shaft.

13. In a fluid meter; the combination with a wobble plate; of a drive shaft on said wobble plate; a driving block in which said drive shaft is journalled; a crankshaft; a crank arm operatively connected to said crankshaft; means connecting said driving block to said crank arm with freedom of sliding pivotal movement of the block about said means connecting said driving block to said crank arm; and spring loading means for said driving block wherein the forces of said spring loading means are exerted on said wobble plate drive shaft substantially at right angles to the axis of said wobble plate drive shaft.
